UNITED STATES PATENT OFFICE

EARL B. WAGONER, OF LAKewood, OHIO, ASSIGNOR TO THE STANDARD OIL COMPANY,
OF CLEVELAND, OHIO, A CORPORATION OF OHIO

DESIGN FOR A BUILDING

Application filed March 6, 1931. Serial No. 38,971. Term of patent 14 years.

To all whom it may concern:

Be it known that I, EARL B. WAGONER, a citizen of the United States, and a resident of Lakewood, county of Cuyahoga, and State of Ohio, have invented a new, original, and ornamental Design for Buildings, of which the following is a specification, reference being had to the accompanying drawing, forming part thereof.

In said annexed drawing:

Fig. 1 is a perspective view of my design; and Fig. 2 is a plan view on reduced scale.

The general aspect of my design presents an expanse of glazing and panel effect, as will be readily apparent from Fig. 1. The other side of the building design continues in general a similar appearance. The tower on top of the building presents the same appearance on all sides.

I claim:

The ornamental design for a building as shown and described.

Signed by me, this 3rd day of March, 1931.

EARL B. WAGONER.
